[57] ABSTRACT

A dump bin formed of a one piece sheet of corrugated paper board or similar material having an upper tray to receive the product, the upper tray being supported by inwardly projecting portions of the lower sides of the bin and including interlocking means for holding the tray elements in position.

1
DUMP BIN

The invention relates to dump bins for displaying products in either a random or orderly arrangement for point of sale display in stores such as supermarkets.

The invention is more particularly directed toward providing such a dump bin which has an upper tray and a lower support structure and is formed from a single piece of material from stock such as corrugated paper board or cardboard.

Most prior art dump bins, which were formed from corrugated paper board or similar material, were either difficult to erect at the point of display or were weak and unstable. Most of them were made of more than one piece and it was therefore more difficult for a salesman or a demonstrator to erect them quickly and easily.

Corrugated paper board and similar material lends itself to the fabrication of tubular shapes from a flat, one-piece sheet whose pattern is cut and scored to facilitate the erection of a finished dump bin. For a long time, need has existed for a readily erectable, single piece, dump bin which may be erected and used at the point of sale and/or display and which may be carried flat by one person.

Broadly, the invention provides a tubular unit formed from a single sheet and which has a lower base and an upper tray. There are at least two side panels each of which projects inwardly from a side of the tubular unit. The side panels are partially severed from and partially joined to the sides from which they project. The upper tray is formed by top panels. Preferably four if the tubular unit is four sided, which fold into the top of the tube and are supported by the inwardly projecting side panels.

Accordingly, it is an important object of the invention to provide a tubular unit formed of a single piece of material and which has an upper tray and a lower support for supporting the tray.

It is a further object of the invention to provide such a unit wherein the upper tray panels interlock with the inwardly projecting side panels.

It is a still further object of the invention to provide such a unit wherein the inwardly projecting side panels interlock with each other.

It is yet another object of the invention to provide such a unit wherein the top panels interlock with each other.

It is a still further object of the invention to provide such a unit wherein the top panels interlock with each other and with the inwardly projecting side panels.

These and other objects, advantages, features and uses will be apparent during the course of the following description, when taken in conjunction with the accompanying drawings, wherein:

FIG. 1 is a perspective of one embodiment of erected dump bin of the invention;

FIG. 2 is a top plan view of the embodiment of FIG. 1 after two of the top panels have been folded into position;

FIG. 3 is a vertical sectional view taken along the lines 3-3 of FIG. 2, viewed in the direction of the arrows;

FIG. 4 is a pattern of a further embodiment of dump bin of the invention;

2

FIG. 5 is a broken-away perspective view showing a partially erected dump bin formed from the pattern of FIG. 4;

FIG. 6 is a perspective view of the completely erected dump bin formed from the pattern of FIG. 4;

FIGS. 7, 8, 10 and 11 are perspective view of completed dump bins of the invention showing various side panel configurations;

FIG. 9 is a perspective view of a completed three-sided dump bin of the invention;

FIG. 12 is a pattern of another embodiment of dump bin of the invention;

FIG. 13 is a partial pattern of still another embodiment of the invention;

FIG. 14 is a broken-away perspective view of a partially erected dump bin which is formed from the pattern of FIG. 13; and

FIG. 15 is a perspective view of the dump bin formed from the pattern of FIG. 13.

In the drawings, wherein, for the purpose of illustration, there are shown various embodiments of the dump bin of the invention, the numeral 20 designates a completed dump bin (FIG. 1). Dump bin 20 is formed of a single piece of material such as corrugated paper board and is seen to be a tubular, four-sided figure.

An upper tray 22 is formed above the lower base and has four top panels 24 which are folded to form the tray 22 which is supported by inwardly projecting panels 26 which are partially severed from and partially joined to their associated sides 28 as shown at 30 and 32, respectively. The lower base is formed by the sides 28 when the unit is expanded as shown in FIG. 1.

Each top panel is provided with a slot 34 which is engaged by a projection 36 on a side panel 26. The top panels are scored as shown at 38 so that when they are folded down into the inside of the tube, portion 40 helps to form the horizontal portion of the tray and portion 42 forms a portion of the side of the tray.

To improve the stability of the upper tray, two opposite panels 42 are provided with a projection 44 on each edge, each of which interlocks with a slot 46 which is located adjacent an edge of the other two opposite panels 42.

To erect the dump bin of FIG. 3, the tube, which has been joined by a "manufacturer's joint" and is transported folded and flat, is expanded and the side panels 26 are pushed in. Two opposite top panels 24 are folded down and the projections 36 are engaged in their associated slots 34. Then the other two top panels are folded down so that their slots 34 are engaged by their associated projections 36 and the projections 44 are engaged in their associated slots 46. Now, product of considerable weight and bulk may be placed in the upper tray for display and/or sale.

FIG. 4 is a pattern of another embodiment of the invention. It is formed of a flat, single sheet 50 which is cut as shown by the solid lines and scored as shown by the dashed lines. The manufacturer's joint is formed by folding on score line 54 and wrapping edge 52 around edge 56 so that score line 54 contacts edge 56. The joint is then suitably fastened by gummed tape, staples, glue or any other means. All the dump bins of the invention, illustrated and described herein, are made in the same manner as has just been described and are preferably delivered to the user in tubular form, folded

flat. Of course, the units can be delivered in pattern form and the manufacturer's joint may be field fabricated but such a technique would be time consuming and wasteful. Pattern 50 is seen to have four top panels 58 and four side panels 60. The side panels 60 are provided at their upper opposite corners with a slot 62 and a hook 64 arranged so that adjacent side panels may be interlocked to each other. If desired, interlocking between the side panels and the top panels may also be provided using the constructions which we have described earlier.

Erection proceeds by pushing in side panels 60 and locking them as shown in FIG. 5. After the side panels have been locked in place, the top panels 58 are folded in place to obtain the bin of FIG. 6 which is now ready to receive product.

FIGS. 7, 8, 10 and 11 are perspective views which show various illustrative side panels of varying shapes to demonstrate the versatility and commercial feasibility of the invention.

Panel 66 (FIG. 7) is scored as shown at 68 so that it can be folded to provide additional support for the upper tray 70. All the side panels may be scored or only one or two may be scored. Panel 72 is scored at 74 for the same purpose as has just been described (FIG. 8).

Panels 78 (FIG. 10) and 80 (FIG. 11) both demonstrate the versatility in design which can be achieved by utilizing the basic teaching of the invention. Panel 78 is scored at 82 for the same purpose as has already been described.

FIG. 9 is a perspective of a three-sided tubular unit of the invention having an upper tray 77, sides 79 with inwardly projecting, side panels 81. Its erection and use is the same as those already described. The upper tray 77 is interlocked with the side panels 81 in the same manner as is the bin 20 of FIG. 1.

The pattern of FIG. 12 may be used for forming the bin of FIG. 1 or FIG. 7 as will be evident from the following discussion. Sheet 84 is a single sheet and ends 86 and 90 and score line 88 are used to form the manufacturer's joint. Side panels 92 are a part of sides 94 and are severed from the sides as shown by the solid lines 98 and are scored by the dashed lines 100. Partial slots 99 and cutouts 101 serve to align the top panels and provide clearance for projections 36 (FIG. 1).

The second side panel 92 from the left is provided with scores 102 and if all panels were so formed, we then have the embodiment of FIG. 7. If the side panels of the figure are unscored, we then have the embodiment of FIG. 1.

The dump bin 110 of FIGS. 13-15 is a four-sided tubular unit wherein only two side panels project inwardly to support the upper tray. A pair of inwardly projecting, opposite side panels 112 are severed at their top from their respective sides and are scored as shown at 114, 116 and 118. The top panels 120 are in three sections 122, 124 and 126 and are provided with interlocking projections 128 and slots 130.

When side panel 112 is pushed in, it expands a pair of gussets 132 which help support the upper tray when the top panels 120 are folded down as shown in FIG. 14. When all four top panels 120 are folded down, the finished bin of FIG. 15 is formed.

While particular embodiments of the invention have been shown and described, it is apparent to those

skilled in the art that modifications are possible without departing from the spirit of the invention or the scope of the subjoined claims.

The embodiments of the invention in which an exclusive property or privilege is claimed are defined as follows:

1. In a dump bin formed of a one-piece sheet and an erected, four-sided tubular shape with a lower base and an upper tray to receive products for display therein, the improvement which comprises:

four side panels projecting inwardly from the sides of the lower base;

at least two top panels folded inwardly from the top of the sheet to form the upper tray;

each of the side panels being partially severed from the side of which it is a part and being partially joined thereto;

the side panels being provided with projections and the top panels being provided with slots to receive the projections such that when the tubular shape is erected, the inwardly projecting side panels interlock with the inwardly folded top panels to make the support for the upper tray stable.

2. The invention of claim 1 wherein:

there are four top panels;

there is a projection on each edge of two opposite top panels; and

there is a slot adjacent each edge of the other two opposite top panels to receive a projection and to impart further stability to the upper tray.

3. The invention of claim 1, wherein the inwardly projecting side panels are scored and bent at an angle to make the support for the upper tray more stable.

4. In a dump bin formed of a one-piece sheet and an erected, four-sided tubular shape with a lower base and an upper tray to receive products for display therein, the improvement which comprises:

four side panels projecting inwardly from the sides of the lower base;

at least two top panels folded inwardly from the top of the sheet to form the upper tray;

each of the side panels projecting inwardly from the base being partially severed from the side of which it is a part and being partially joined thereto;

each of the side panels having a slot at one corner and a hook-shaped projection at the other corner to engage the slot in the adjacent side panel such that when the tubular shape is erected, the inwardly projecting side panels make the support for the upper tray formed by the inwardly folded top panels stable.

5. In a dump bin formed of a one-piece sheet and an erected, four-sided tubular shape with a lower base and an upper tray to receive products for display therein, the improvement which comprises:

two side panels projecting inwardly from opposite sides of the erected tubular shape;

four top panels being folded inwardly from the top of the sheet to form the upper tray;

the side panels being severed from the sides from which they project and being connected to said sides by a pair of side gussets;

each of two opposite top panels having a projection on the edge thereof;

each of the other two opposite top panels having a slot adjacent the edge thereof to receive the projections;

the upper tray being formed by the inwardly folded top panels which are cooperatively locked by the 5 projections and slots and being supported by the inwardly projecting side panels to make the support of the upper tray stable.

6. In a dump bin formed of a one-piece sheet and an erected, three-sided tubular shape with a lower base and an upper tray to receive products for display 10 therein, the improvement which comprises:

three side panels projecting inwardly from the sides

of the tubular shape; the side panels being partially severed from the sides from which they project and being partially joined thereto;

three top panels folded inwardly from the top of the sheet to form the upper tray;

the side panels being provided with projections and the top panels being provided with slots to receive the projections such that when the tubular shape is erected the inwardly projecting side panels interlock with the inwardly folded top panels to make the support for the upper tray stable.
